UNITED STATES PATENT OFFICE.

HEINRICH MÜLLER, OF NUERMBERG, GERMANY.

TOY FIGURE COVERED WITH FABRIC.

Application filed April 2, 1923. Serial No. 629,453.

It is a well known fact that it is impossible or very difficult to produce stuffed toy figures of fabric in small sizes in good imitations true to nature. The reason therefore is that the fineness of the lines and of the expression are very much obliterated owing to the comparatively coarse stuffing material used, this inconvenience increasing the smaller the figures are. The sewing work becomes more difficult the smaller the size of the figures is so that sufficiently clever seamstresses are not available in sufficient number.

This invention has for its object to produce fabric covered figures without body or members stuffed with a soft material with the aid of hollow parts pressed from sheet metal or similar material. It is evident that with figures of this type other measures are necessary as hitherto used for the manufacturing of the fabric figures of known type. It has become known per se to cover with fabric hollow toy figures of resistable material. This is done for instance in such a manner that the pieces of fabric cut out accordingly are simply glued upon the toy figure. It is however impossible to produce in this manner toy figures of natural appearance similar to the plush figures made by hand. On the one hand the pieces of fabric, specially if plush is used, would protrude very strongly and on the other hand it would be impossible to make the fabric fit tightly upon the surface of the body merely by gluing specially at parts of the body like the face, the snout, the ears or around the eyes, especially as glue does not adhere easily on sheet metal.

A figure according to this invention is covered with fabric in such a manner that it is of absolutely natural appearance. In order to attain this result, inwardly projecting teeth are arranged in proximity to the edges of the several hollow parts for composing the figure, these teeth being designed to grip into the fabric after the corresponding hollow part in the edge of the same has been covered with the fabric. The invention relates further to different arrangements which permit to form the several members of the figure and to compose the figure after all the parts have been covered with fabric. The difficulties which are caused at the putting together of the figure by the necessity to be very careful on

account of the fabric which covers the different parts and the good appearance has to be preserved are avoided according to this invention.

The invention has further for its object to construct the figure in such a manner that the mechanisms for producing the rotating and nodding movements of the head can be easily mounted in the figure and that at the same time the cover of fabric can be securely fixed in proximity of the parts in question.

A toy figure and the several parts of the same are shown by way of example on the accompanying drawings.

Figs. 1 and 2 show the toy figure in two longitudinal sections standing at right angles the one to the other.

Fig. 3 shows in elevation and cross section the part of a plane piece of sheet metal designed for making parts of the body.

Fig. 4 shows a disk which is designed for holding together the two parts of the body of the figure.

Figs. 5 and 6 show the parts forming respectively an arm and a leg of the figure placed flat upon a surface.

Fig. 7 shows two disks to be mounted in the head placed on the same plan.

Fig. 8 is a vertical section showing the two disks (Fig. 7) ready to be mounted in the head.

Figs. 9 and 10 are a side elevation and front elevation respectively of the head.

Fig. 11 shows the piece of sheet metal designed to form the ears at the state before it is bent to proper shape.

Fig. 12 is a horizontal section through the head.

The several parts of the body of the figure are each formed of one or two hollow pressed pieces of sheet metal which are either to be assembled or to be connected by bending after they have been covered with fabric. In order to ensure that the fabric adheres to these parts teeth 2 are cut out of the pieces of sheet metal 1 (Fig. 3) in proximity to the edge of the same, said teeth being bent upward. The fabric 3, which is indicated in Fig. 3 by dash and dot lines, is fixed upon the teeth 2, whereupon the ends of these teeth are bent up. The fabric is thus securely attached to the piece of sheet metal.

The arms and legs (Figs. 5 and 6) consist

each of one single piece of sheet metal the identical halves of which are pressed hollow. In order that the pieces 4 for the arms and the pieces 5 for the legs can be easily bent around their middle axis, slits 6, 6 respectively 7, 7 extending along the middle lines are cut out. The sheet iron at the parts 8, 8 is pressed outwardly to form grooves of semi-circular cross section so that, after 10 the sheet iron has been bent along the middle line, smooth round ribs are formed. In proximity to the edge of the pieces of sheet iron pointed tongues 2 are stamped out of the material into which the fabric is to be 15 hooked. The two parts of the arms and legs are held together with the aid of connecting flaps 9 and 10 stamped out in one half of the piece of sheet metal and having at the front edge small extensions 11 respectively 12. In the outer half of the piece of sheet metal slits 13 and 14 are provided which are designed to receive the projections 11, 12 respectively of the connecting pieces 9 and 10, the ends of the projections 20 projecting through the slits being bent over with the aid of needles stuck through the fabric.

Any number of connecting or cross pieces can be provided. For the legs a second 30 connecting piece or cross piece 15 and corresponding slit 16 is provided near the lower edge which not only serves for connecting the two halves of the leg but also for supporting a foot plate 17 (Figs. 1 and 2) which may be covered with felt or fabric. This lower cross piece 15 has pointed extensions 18 at either side which are designed to penetrate into the foot plate to securely hold the same when they 35 have been bent down. The arms remain open at the lower ends so that pieces of other fabric than that used for covering the toy figure may be inserted to form the hands or paws. The arms and the legs are 40 connected with the body of the figure by means of transverse axles 20 and 21 (Fig. 2). These axles are preferably tubular and have at either end a flap 22, 23 respectively adapted to be bent with the aid of pins 45 stuck through the fabric. In order to facilitate the insertion of the axles cavities are pressed into the body of the arms or legs at convenient points as shown in Fig. 2. The outer cavities 24 of the arms and legs are inwardly directed so that the axles 50 can be inserted directly into the hole at the bottom of the cavities. Upon the inner side of the arms and legs on the one hand and at the corresponding point of the body 55 on the other hand cavities and bosses 25, 26 and 27, 28 respectively are provided which engage into one another. The holes at the bottom of these cavities and at the 60 apexes of the bosses register so that the axles can be easily inserted through the

same. The flaps 22, 23 are located after they have been bent over, in the outer cavities 24, 24 so that the cover of fabric shows a smooth surface at the articulations. The cavities present further the 70 advantage that the arms and legs are securely mounted even if the holes are larger than the cross section of the axle. Instead of tubular axles a wire could be used and the ends of the same would be 75 notched in order to facilitate the bending over. The two halves of the body 29 are held together by the neck plate 30 and transverse plate 31. The transverse plate has at its edge a number of flaps 32 (Fig. 80 4). Corresponding with the flaps 32 small slits are provided in the wall of the body through which the flaps 32 project. By bending over the outer projecting ends of said flaps the secure connection between 85 the parts of the body is produced. In the front part of the connecting plate 31 an incision 33 is arranged into which the edge of the fabric which covers the body is pressed with the aid of a pin or a rod to be guided along the seam from above to below. The body could also be made in 90 one piece similar to the arms and legs.

If the figure, as is frequently the case, is fitted with a sound-producing device a 95 vertical partition 77 indicated in dash and dot lines in Fig. 1 is arranged in the body upon which the sound producing device is mounted the front wall of which is curved according to the shape of the body. The neck plate 30 can be fixed in the body in a similar manner as the cross plate 31 or the pointed flaps could be provided at the upper edge of the body the corresponding 100 slits being provided in the neck plate. The neck plate has further pointed hooks 105 34 designed to hold the edge of the fabric.

The figure shown on the drawing is of such a construction that the head can 110 execute rotating and nodding movements. The head is fixed by means of a pivot pin 35 upon a tubular support 36 which is supported by the neck plate 30 and the cross plate 31 so that it can also rotate 115 in these plates but is secured against displacement in longitudinal direction. With this object in view the ends of the tube 36 are cut in and bent up below plate 31 and above plate 30 so that flaps 37 and 38 are 120 formed. In order to enable the lower end of the tube to be inserted through corresponding holes of the two plates together with the flaps 38 slits 39 are provided extending from the holes in said plates (Fig. 125 4). The flaps 38 are bent over after the tubular support has been inserted through a hole 40 in the wall of the body so that said flaps adopt the positions shown in Fig. 4 in dash lines.

A rod 41 is inserted in the tubular sup-

port 36 by means of which movements of the head of the figure may be produced either by longitudinal displacement or by rotation of said rod.

- 5 The head is composed of two halves 42, 43 (Fig. 12). In each half a disk 44 and 45 is arranged near the edge (Fig. 7). At the edges of said disks flaps 46 are arranged which are designed to be inserted 10 through slits of the two halves of the head and to be bent over. Stays 48 and 49 with end flaps are cut out of plate 44 designed to be inserted through slits 50, 51 of plate 45 after the stays have been bent to the 15 horizontal position. By the stays 48, 49 the flaps of which are bent over by means of pins or the like inserted through holes provided in the wall of the head, the two disks 44, 45 are held in determined distance 20 apart so that the edges of the halves of the head join.

The disks 44 and 45 are not only secured in their initial positions by the stays 48, 49 but further by means of cavities 53 the outer 25 walls of which are in contact. At the point of contact a flap 47 is stamped out which serves for holding the disks together at this point. The disks have further pointed teeth 54 at the lower edge. The edges of the two 30 parts of the head recede at this point so far that they are situated in the plane of the disks. In this manner a large gap 52 is formed in the lower surface of the head (Figs. 2 and 12) through which the support 36 projects. The fabric for covering the 35 head is hooked on the pointed teeth 54 whereupon said teeth are bent over inwardly against the disks. The pointed teeth 54 project therefore slightly into the gap in the 40 lower surface of the head. In order to prevent the pointed teeth 54 from coming in contact with the support 36 of the head when the head is oscillated cavities 55 are arranged in the lower parts of the disks (Fig. 8). 45 The axle 35 has ring-shaped columns 78 so that the disks 44, 45 can oscillate as much as possible without friction. A cross bar 48 serves as point of attack for the rod 41. In this cross bar a recess 56 is arranged with 50 which the upper hook-shaped end of the rod 41 engages. When the head is being covered with a piece of fabric which has been cut to a convenient pattern some of the fabric will be left over at the one side of the head. In 55 order to hide this part of the fabric a gap 57 (Fig. 9) is provided at the side of the head into which this excessive fabric is inserted. The edges of the gap 57 have an inwardly projecting burr which securely retains the fabric.

The ears are cut out of a separate piece of sheet iron which has the initial shape shown in Fig. 11. This piece of sheet iron has incisions 58, 59 by which at each side two flaps 60, 61 in the shape of an ear are formed.

The flaps are bent along the line *a*—*b* so that a double flap is formed which is again bent upward along the line *c*—*c*. The remaining part is curved according to the curvature of the head. In the head a flat cavity similar 70 in shape to the base of the finished ear is provided so that this base does not project from the surface of the head.

The ear is fixed on the head in incisions 63, 64 through which teeth 46 of the disks 44, 45 project. Owing to this arrangement the 75 ears serve at the same time as connection for the two halves of the head.

At the ears some of the fabric will also be left over when the head is being covered. 80 This fabric in excess is pushed between the two flaps of each ear. In order to secure the fabric at this part pointed teeth 65 (Fig. 11) are stamped out of the flaps 60, 60 and slits 66 are provided in the flap 61 through which the teeth are inserted after the fabric has been pushed in. The points of the teeth which are to be bent over afterwards serve at the same time for securing in position the 85 part of the fabric which is folded to imitate the shell of the ear.

In the wall of the head cavities 67 with 90 incisions are arranged. These cavities are designed to receive the eyes which have studs at the back designed to engage with said incisions. In the wall of the head holes 68 are arranged in proximity of the eyes in order to permit of bending the studs over against the inner side of the wall of the head. The eyes serve at the same time for holding 95 the fabric. The orbits are comparatively deep so that the fabric can be pulled through the eyes into the inward curve 70 at the bridge of the nose (Fig. 9) provided at the 100 root of the nose.

Holes 71, 72 are provided in the wall of the head which serve for the production of the snout the sewing through these holes being done in the manner shown in Fig. 10.

The sewing thread 74 serves at the same 105 time for uniting the two halves of the head. The sewing holes permit further to bend over the ends of the stays 48 and 49 of the disks 44 and 45 but special holes could also be provided for this purpose.

The connection of these disks 44, 45 with the halves of the head is shown in Fig. 9. Some of the studs 46 are bent over forwardly 110 and the others backwardly in order to ensure a secure connection. According to the arrangement of the disks the tenon-jointing of the edges of the halves of the head may be omitted and the fabric may be pressed into the gap 73 (Fig. 12) between the two 115 halves of the head.

I claim:—

1. A fabric-covered toy figure comprising in combination a head, a body and members of the body open at one end and made each by hollow pressing from convenient mate- 120

rial, inwardly projecting teeth stamped out of the material of each hollow pressed part near the edge of the open end of said parts, and a cover of fabric for each hollow pressed part folded over the edge of the open end of the part and stuck on said teeth which are folded over to securely hold said fabric cover in the stretched position.

2. A fabric-covered toy figure comprising
10 in combination a head, a body and members of the body open at one end and made each by hollow pressing from convenient material each hollow pressed part having slits, transverse plates in said hollow pressed parts, extensions at the ends of said transverse plates projecting through said slits, inwardly projecting teeth stamped out of the material of each hollow pressed part near the edge of the open end of said parts, and
15 a cover of fabric for each hollow pressed part folded over the edge of the open end of the part and stuck on said teeth which are folded over to securely hold said fabric cover in the stretched position.

25 3. A fabric covered toy figure comprising in combination a head, a body and members of the body open at one end and made each by hollow pressing from convenient material each hollow pressed part having slits, 30 transverse plates in said hollow pressed parts, having recesses at the proximity of a joint of the parts of the body, extensions at the ends of said transverse plates projecting through said slits, inwardly projecting teeth stamped out of the material of each hollow pressed part near the edge of the open end of said parts, and a cover of fabric for each hollow pressed part folded over the edge of the open end of the part and stuck on said teeth which are folded over to securely hold said fabric cover in the stretched position, said fabric covers being stuffed into the recesses of the transverse plates through the joint of the body.

45 4. A fabric covered toy figure comprising in combination a body composed of two hollow pressed parts, two arms and two legs each consisting of a foldable hollow pressed piece of sheet metal having short vertical slots at the middle line and outwardly pressed grooves of semi-circular cross section in the inner surface of the parts between said slots so that the folding of said pieces of sheet metal is facilitated, covers of fabric 50 on said parts of the toy body and means for attaching said arms and legs to said body.

55 5. A fabric covered toy figure comprising in combination a head, a body and the members of the body all open at one end and made each in two parts by hollow pressing from convenient material, inwardly projecting teeth in proximity of the edges at the open ends of the hollow pressed parts, slits 60 in one part of each arm and leg and a

flap with projection at the end stamped out of the other part of each arm and leg designed to be bent to the horizontal position so that the projections are inserted through said slits, said flaps serving as stays for securely connecting the two parts of each arm and leg, and a fabric stretched over the hollow parts and the edges thereof and securely held by said teeth which are bent over.

75 6. A fabric covered toy figure comprising in combination a head, a body and two legs and two arms of the body open at one end and made each by hollow pressing from convenient material said legs and arms being each composed of two halves, inwardly projecting teeth in proximity of the edges of the open ends of the hollow pressed parts, slits in one side part of each arm and leg and a flap with projection at the end stamped out of the other part of each arm and leg designed to be bent to the horizontal position so that the projections are inserted through said slits, said flaps serving as stays for securely connecting the two parts of each arm and leg, and a flap stamped out of one half of the leg piece near the lower edge of the same designed to serve as cross stay, a foot plate attached to said lower stay, and a fabric stretched over the hollow parts and the edges thereof and securely held by said teeth which are bent over.

95 7. A fabric covered toy figure comprising in combination a head, a body and two legs and two arms of the body open at one end and made each by hollow pressing from convenient material said legs and arms being each composed of two halves, inwardly projecting teeth in proximity of the edges of the open ends of the hollow pressed parts, 100 slits in one side part of each arm and leg and a flap with projection at the end stamped out of the other part of each arm and leg designed to be bent to the horizontal position so that the projections are inserted through said slits, said flaps serving as stays for securely connecting the two parts of each arm and leg, and a flap stamped out of one part of the leg piece near the lower edge of the same designed to serve as cross stay, a foot plate attached to said lower stay, teeth at the edge of said lower stay, designed to penetrate into the foot plate and to securely hold the same after they have been 105 bent down.

110 8. A fabric covered toy figure comprising in combination a head composed of two halves of hollow pressed sheet metal, a body composed of two hollow pressed halves, two disks, one in each half of the head near the edge of said half, teeth and flaps stamped out of said disks for connecting the same on the one hand with the two halves of the head and on the other hand one disk with 115 the other in such a manner that at the up- 120

per end of the body a gap is formed, two arms and two legs each composed of hollow pressed parts, inwardly projecting teeth in proximity of the edges of all the hollow pressed parts, and means for attaching said arms and legs to said body, a piece of fabric stretched over the body, and stuffed into said gap at the upper end of the same, and pieces of fabric covering each arm and each leg 10 securely held by said teeth which are bent over.

9. A fabric covered toy figure comprising in combination a head composed of two halves of hollow pressed sheet metal, a body 15 composed of two hollow pressed halves, two disks, one in each half of the head near the edge of said half, teeth and flaps stamped out of said disks for connecting the same on the one hand with the two halves of the 20 head and on the other hand one disk with the other in such a manner that at the upper end of the body a gap is formed, two arms and two legs each composed of hollow pressed parts, inwardly projecting teeth in 25 proximity of the edges of all the hollow pressed parts, and means for attaching said arms and legs to said body, a piece of fabric stretched over the body, and stuffed into said gap at the upper end of the same, and pieces 30 of fabric covering each arm and each leg securely held by said teeth which are bent over, the ears consisting of a piece of sheet metal cut out to form two flaps of which the one has slits and which are folded together and inserted in the head of the figure, and a piece of fabric for covering said ear part having its edge clamped between said flaps.

10. A fabric covered toy figure comprising in combination a head composed of two halves of hollow pressed sheet metal, a body composed of two hollow pressed halves, two disks, one in each half of the head near the edge of said half, teeth and flaps stamped out of said disks for connecting the same on the one hand with the two halves of the head and on the other hand one disk with the other in such a manner that at the upper end of the body a gap is formed, two arms and two legs each composed of hollow pressed parts, inwardly projecting teeth in proximity of the edges of all the hollow pressed parts, means for attaching said arms and legs to said body, a piece of fabric stretched over the body and stuffed into said gap at the upper end of the same, pieces of fabric covering each arm and each leg securely held by said teeth which are bent over, the ears consisting of a piece of sheet metal cut out to form two flaps of which the one has slits and which are folded together and inserted in the head of the figure, teeth stamped out of the flap which has no slits to be bent up and inserted through the slits of the other part, and a piece of fabric for covering said

ears having its edge clamped between said flaps and held on the ends of the teeth projecting through said slits.

11. A fabric covered toy figure comprising in combination a head composed of two halves of hollow pressed sheet metal having each a recess in the lower edge, a narrow gap being provided on the side of one of said halves of the head, a piece of fabric covering said head having its edges or left over parts stuffed into the lateral gap and into said recesses, a body composed of two hollow pressed halves, two disks, one in each half of the head near the edge of said half, teeth and flaps stamped out of said disks for connecting the same on the one hand with the two halves of the head and on the other hand one disk with the other in such a manner that at the upper end of the body a gap is formed, two arms and two legs each composed of hollow pressed parts, inwardly projecting teeth in proximity of the edges of all the hollow pressed parts, and means for attaching said arms and legs to said body, a piece of fabric stretched over the body, and stuffed into said gap at the upper end of the same, and pieces of fabric covering each arm and each leg.

12. A fabric covered toy figure comprising in combination a head composed of two halves of hollow pressed sheet metal having each a recess in the lower edge, a narrow gap being provided on the side of one of said halves of the head, a piece of fabric covering said head having its edges or left over parts stuffed into the lateral gap and into said recesses, a body composed of two hollow pressed halves, two disks, one in each half of the head near the edge of said half, teeth and flaps stamped out of said disks for connecting the same on the one hand with the two halves of the head and on the other hand one disk with the other in such a manner that at the upper end of the body a gap is formed, two arms and two legs each composed of hollow pressed parts, inwardly projecting teeth in proximity of the edges of all the hollow pressed parts, and means for attaching said arms and legs to said body, a piece of fabric stretched over the body, and stuffed into said gap at the upper end of the same, pieces of fabric covering each arm and each leg securely held by said teeth which are bent over, and teeth at the parts of the edges of the disks which extend over the said recesses, designed to hold the fabric and bent over inwardly so that the recesses are covered by the fabric.

13. A fabric covered toy figure comprising in combination a head adapted to execute rotating and nodding movements composed of two halves of hollow pressed sheet metal having each a recess in the lower edge, a narrow gap being provided on the

6
side of one of said halves of the head, a piece of fabric covering said head having its edges or left over parts stuffed into the lateral gap and into said recesses, a body composed of two hollow pressed halves, two disks, one in each half of the head near the edge of said half, teeth and flaps stamped out of said disks for connecting the same on the one hand with the two halves of the head and on the other hand one disk with the other in such a manner that at the upper end of the body a gap is formed, two arms and two legs each composed of hollow pressed parts, inwardly projecting teeth in proximity of the edges of all the hollow pressed parts, and means for attaching said arms and legs to said body, a piece of fabric stretched over the body, and stuffed into said gap at the upper end of the same, pieces of fabric covering each arm and each leg securely held by said teeth which are bent over, and teeth at the parts of the edges of the disks which extend over the said recesses designed to hold the fabric and 25 bent over inwardly so that the recesses are covered by the fabric, an axle on said disks of the head, a stay for connecting the two disks the one with the other, a support for the axle, and a rod attached to said stay of the disks and projecting with its free end from the body, designed to control the movements of the head.

17. A fabric covered toy figure comprising in combination a head, a body and the members of the body composed of hollow pressed parts having slits, transverse plates positioned one above the other in the body, projections at the ends of said plates engaging with said slits so that they project through said slits, inwardly projecting teeth in proximity of the edges of the hollow pressed parts, and a fabric stretched over the hollow pressed parts and the edges thereof and securely held by said teeth which are bent over and a support for the head, flaps at the upper end of said support designed to be bent so that they bear upon the upper transverse plate and flaps at the lower end of said support designed to be bent so that they bear against the lower surface of the lower transverse plate.
18. A fabric covered toy figure comprising in combination a head composed of two parts of hollow pressed sheet metal having cavities with apertures serving as sockets for the eyes and holes near said apertures, a body and the members of the body composed of hollow pressed parts, means for attaching the members to the body, all the hollow pressed parts being open at one end, inwardly projecting teeth in proximity of the edges of the open ends of the hollow pressed parts, eyes in the cavities, a stud of each eye projecting through the hole in the cavity, and pieces of fabric covering the head, the body, the arms and the legs, said fabric being securely held by said inwardly projecting teeth, the holes in the head serving for inserting a pin through the fabric in order to bend over the studs of the eyes.

the cavity, and pieces of fabric covering the head, the body, the arms and the legs said fabric being securely held by said inwardly projecting teeth, the holes in the head serving for inserting a pin through the fabric in order to bend over the studs of the eyes.

19. A fabric covered toy figure comprising in combination a head composed of two parts of hollow pressed sheet metal having cavities with apertures serving as sockets for the eyes and holes near said apertures, and holes at the part which forms the snout, a body and the members of the body composed of hollow pressed parts, means for attaching the members to the body, all the hollow pressed parts being open at one end, inwardly projecting teeth in proximity of the edges of the open ends of the hollow pressed parts, eyes in the cavities, a stud of each eye projecting through the hole in the cavity, and pieces of fabric covering the head, the body, the arms and the legs, said fabric being securely held by said inwardly projecting teeth, the holes in the head near the eye aperture serving for inserting a pin through the fabric in order to bend over the studs of the eyes.

In testimony whereof I affix my signature.

HEINRICH MÜLLER.
